UNITED STATES PATENT OFFICE.

DAVID NELSON CROSTHWAIT, JR., OF MARSHALLTOWN, IOWA.

APPARATUS FOR RETURNING WATER TO BOILERS.

1,353,457.

Specification of Letters Patent. Patented Sept. 21, 1920.

Application filed December 4, 1916. Serial No. 134,931.

To all whom it may concern:

Be it known that I, DAVID N. CROSTHWAIT, Jr., a citizen of the United States, residing at Marshalltown, in the county of Marshall and State of Iowa, have invented an Improved Apparatus for Returning Water to Boilers, of which the following is a specification.

By my invention water may be fed or returned to a boiler from a level lower than the water line of the boiler. My invention is thus an improvement in water return pumps or traps operated automatically by steam pressure applied to the body of water in the trap, and particularly by aid of an ejector located in the receiver and to which steam is directly admitted.

The details of construction, arrangement and operation of my invention are as hereinabove described, and illustrated in the accompanying drawing, which is in the main a side view of the apparatus, a portion of the water receiver being broken out to show interior parts.

1. *l* indicates a water receiver or trap whose upper portion carries a water inlet pipe *h* having a check valve *i*, and a water discharge pipe *k* having a check valve *j*, and a steam inlet pipe *a* having a valve *b*, whose position is controlled by a float-operated trip mechanism. A horizontal rock shaft extends through the receiver *l* and is provided interiorly of the latter with a float *g*, and exteriorly of the same with a weighted arm *d*, and another arm operatively connected with the valve *b*, but arranged to engage same operatively only at time of tripping. The steam pipe *a* extends into the receiver and has a steam nozzle *c*, in the upper portion of the receiver, while the remaining portion *e* extends along the bottom of the receiver, and is provided with an ejector *f* of the usual type. This ejector pipe communicates with the afore-mentioned water discharge pipe *k* located exteriorly of the receiver.

The operation of the apparatus is as follows:

As the receiver *a* fills with water received from the pipe *h* the float *g* will rise, and when the water has reached a certain height in the tank, the tripping mechanism, of which the weighted lever *d* forms a principal part, will effect the closure of the valve *b* against the atmosphere which, up to this

time, will have been in communication with the same, and will thus open the passage in the pipe *a*. The latter being suitably connected with the boiler, above the water level therein, when opened, allows steam to pass through *b* into the receiver *l* and discharge through the nozzle *c*, so that it exerts a pressure on the surface of the water, forcing it into the suction portion of the ejector *f*. Simultaneously, a portion of the steam flowing through the valve will pass down through the pipe *e* to the ejector and thus operate to force the water from the receiver *l* past the check valve *j* and into the pipe *k*, which communicates with the boiler, or it may be in any other receptacle in which water of condensation is to be discharged.

In further explanation of the operation of the apparatus I will state:

When the steam is turned into the trap, it will be diverted in two directions, one part going to the ejector and the other going into the receiver. Due to the large volume of water and the large surface of same that will be exposed, the steam entering here will be rapidly condensed for the first part of the steam admission period. This, would give the ejector a chance to build up a pressure in the combining tube, which meanwhile the water could escape through the suction of the injector to the tank. Further than this, the steam supply would be so arranged that the steam supply to the ejector would have the preference. Shortly the pressure on the surface of the water in the reservoir would build up equal to boiler pressure, and by this time the operation of the injector will have been established. The operation would then continue until the steam supply was cut off.

As the water in the receiver *l* is lowered, the float *g* necessarily falls also, and thus through the trip mechanism *d* operates to close the valve *b*, breaking communication with the pipe *a* and again establishing communication with the atmosphere.

The arrangement of the steam pipe nozzle and the ejector within the receiver is attended by obvious advantages in respect to reduction of space, economy of construction and material, and effectiveness in operation.

I claim:

1. In an apparatus of the character described, a receiver having a water inlet and a delivery outlet to the boiler, a steam sup-

ply pipe, a steam inlet from said steam supply pipe to above the water level of said receiver, a pipe connecting said steam supply pipe and said delivery outlet having a portion submerged in the water of said receiver, an ejector arranged in said submerged portion whereby the water from said receiver is injected into the boiler through said delivery outlet.

10 2. In an apparatus of the character described, a receiver having a water inlet and a delivery outlet to the boiler, a steam supply pipe, a steam inlet from said steam supply pipe to above the water level of said receiver, a pipe connecting said steam supply pipe and said delivery outlet and having a portion submerged in the water of said receiver, an ejector arranged in said submerged portion and means automatically controlling the admission of steam from

15 20 said steam supply pipe to said steam inlet and said ejector whereby the water from

said receiver is periodically injected into the boiler through said delivery outlet.

3. In an apparatus of the character described, a receiver having a water inlet and a delivery outlet to the boiler, a steam supply pipe, a steam inlet from said steam supply pipe to above the water level in said receiver, a pipe connecting said steam supply pipe and said delivery outlet and having a portion submerged in the water of said receiver, an ejector arranged in said submerged portion, and a float-controlled valve mechanism for regulating the admission of steam to said steam inlet and said injector whereby the water from said receiver is periodically injected into the boiler through said delivery outlet.
